UNITED STATES PATENT OFFICE.

WILLIAM C. CUTLER, OF GLENDALE, CALIFORNIA.

DESIGN FOR A VENDING-MACHINE CASING.

Application filed September 2, 1925. Serial No. 14,694. Term of patent 7 years.

To all whom it may concern:

Be it known that I, WILLIAM C. CUTLER, residing at Glendale, in the county of Los Angeles and State of California, have invented a new, original, and ornamental Design for Vending-Machine Casing, of which the following is a specification, reference being had to the accompanying drawing, forming a part thereof.

The figure is a perspective view of a vending machine casing showing my new design.

I claim:

The ornamental design for a vending machine casing as shown,

WILLIAM C. CUTLER.
